UNITED STATES PATENT OFFICE.

JACOB HOCHBERG, OF BROOKLYN, NEW YORK.

BLOOMER CONSTRUCTION.

Application filed October 20, 1923. Serial No. 669,838.

To all whom it may concern:

Be it known that I, JACOB HOCHBERG, a citizen of the United States, and a resident of the city of New York, borough of Brooklyn, in the county of Kings and State of New York, have invented a new and improved Bloomer Construction, of which the following is a full, clear, and exact description.

10 This invention has relation to garments and has particular reference to an improvement in ladies' bloomers.

The principal object of the present invention is to provide a bloomer construction which while affording ample seat room in order not to restrain the movements of the body and limbs when worn, will effect a neat fit at the waist whereby the outer garments will lie smoothly at this point.

20 As a further object the invention contemplates a bloomer construction which is comparatively simple and inexpensive and which is highly efficient in its purpose.

With the above recited and other objects in view, the invention resides in the novel construction set forth in the following specification, particularly pointed out in the appended claims and illustrated in the accompanying drawings, it being understood 30 that the right is reserved to embodiments other than those actually illustrated herein to the full extent indicated by the general meaning of the terms in which the claims are expressed.

35 In the drawings—

The figure is a rear view of the bloomers in applied position.

Referring to the drawings by characters of reference 10 designates generally a pair of bloomers having a rear inserted seat piece 11 which is of sufficient fullness to afford ample seat room. The seat piece 11 terminates an appropriate distance from the upper edge of the garment, which upper edge is gathered as at 12 and secured by a line of stitching 13 to the inserted rear waistband strip 14, which waistband strip

is of lesser length than the width of the seat piece in order that the same will fit smoothly around the waist of the wearer to 50 prevent puckering or bulkiness when the garment is applied. The upper edge of the waistband of the garment is Shirred as at 15 and provided with the usual elastic or contractile band. Under this arrangement and 55 construction it will be noted that the required fullness is given to the seat of the garment at a sufficient distance below the waist line to admit of freedom of movement of the limbs while bulkiness at the waist is 60 eliminated in order that the outer garments will lie smoothly at this point.

I claim:

1. As a new article of manufacture a bloomer construction comprising front and 65 side sections, said sections continuous from the knee to waist line and the side sections extending materially to the rear, an inserted seat piece connected to the rear edges of the side sections from knee to a point 70 materially below the upper edges thereof, and a rear waistband strip of less width than the seat piece sewed to the rear edges of the side sections above the seat piece, said seat piece being gathered at the upper 75 edge and sewed to the lower edge of the inserted rear waistband strip.

2. As a new article of manufacture, a bloomer construction comprising a front body and leg portions extending around the 80 front and sides and to the rear of the wearer, said sections defining a rear opening from knee to waist line, an inserted seat piece sewed at its side edge to the rear edges of the leg side sections from knee to a point below 85 the waist line said seat section gathered at its upper edge, and a rear waistband strip of less width than the seat piece sewed to the rear edges of the side sections and at its lower end to the gathered upper end of the 90 seat piece, said seat piece being of greater width than the said rear opening and transversely expansible to afford ample seat room.

JACOB HOCHBERG.
